UNITED STATES PATENT OFFICE.

HARVEY M. DE LINE, OF SYRACUSE, NEW YORK.

CUTTER AND SHREDDER.

1,086,654.

Specification of Letters Patent.

Patented Feb. 10, 1914.

Application filed November 27, 1912. Serial No. 733,822.

To all whom it may concern:

Be it known that I, HARVEY M. DE LINE, of 313 Kellogg street, Syracuse, in the county of Onondaga, in the State of New York, 5 have invented new and useful Improvements in Cutters and Shredders, of which the following, taken in connection with the accompanying drawings, is a full, clear, and exact description.

10 This invention relates to certain improvements in cutters and shredders, and pertains more particularly to that class of machines used for cutting and shredding vegetables, as cabbage.

15 The object of my invention is to provide a simple and improved machine whereby the material operated on may be either cut, shredded, or cut and shredded, with great regularity and rapidity.

20 A further object is to provide means for holding the knives or knife supporting members firmly but removably in operative position.

Another object is to provide means for 25 supporting the cutting knives in predetermined positions relative to each other.

Other objects and uses will appear from the following description:

In the drawings—Figure 1 is a perspective view of the machine. Fig. 2 is a cross section on line 2—2, Fig. 1. Fig. 3 is a cross section on line 3—3, Fig. 1. Fig. 4 is a cross section through one of the cutting-knife supporting members, showing the 35 means for holding the knife in place. Fig. 5 is a similar section adjacent the knife plate. Fig. 6 is a view of the angle bar of the cutting-knife supporting member, showing the slots for receiving the knives. Fig.

40 Fig. 7 shows the dog seated in a groove in the angle bar for holding the knife supporting member in operative position. Fig. 8 is a perspective view of the shredding knife, showing the groove in which a pivoted dog 45 is seated for holding the knife in place. Fig. 9 shows a slightly different construction for holding the knife or knife supporting member in operative position, comprising a spring adapted to resiliently close the 50 opening in which the knife or knife supporting member is seated.

The machine comprises a body —1— of sheet metal, wood or other suitable material, having supporting legs —2— fastened there- 55 to in any suitable manner, as by screws —3—. The body —1— is provided with

bearings —4— for the reception of a shaft —5—, having one end provided with any suitable driving member as a pulley —6—. Keyed to the shaft by means of set screws 60 —7—, are circular sheet metal plates —8— and —9— having connecting rods as —10— uniting them firmly together. Each of the cylindrical plates —8— and —9— have co-acting apertures —10'— and —11—, the 65 aperture —11— adapted to receive a shredding knife —12—, having a groove —13— in one edge thereof for receiving a dog —14— adapted to hold the knife in place.

The cutting knives —15— are formed 70 preferably of thin sheet metal and have a substantially semi-circular outer portion adapted to form the blade of the knife.

The supporting member for the cutting knives —15— is formed of an angle bar 75 —16— having slots —17— therein for receiving a knife. Each knife —15— is provided with a groove —18— upon its opposite sides, forming projecting flanges —19— upon the blade portion of the knife and 80 —20— upon the rear portion thereof. The side —21— of the angle bar —16— is adapted to fit in one of these grooves and a sheet metal strip —22— is adapted to fit in the other and is held in position between the 85 flanges —19— and —20—. The angle bar —16— and the strip —22— are connected for holding the knives in operative position, by any suitable means as bolts —23—. One end of the knife bearing member is then in- 90 inserted from the inner side into an opening —10'— in one of the plates as —8— and pushed through a sufficient distance until the other end is in position to be inserted in a corresponding opening —10'— in the plate 95 —9—. A dog —28— pivoted to the plate —8— is then pushed over until it engages a groove —24— in the angle bar —16— for holding the knife bearing member in operative position. The device is provided 100 with a cover —25— hinged in any suitable manner to the body —1— and adapted to partially cover the rotating member.

In Fig. 9 I have shown the cutting-knife supporting member, comprising the angle 105 bar —21— and the plate —22—, resiliently held in the openings —10'— by means of a metal strip —26— attached to the plate —8— in any suitable manner, as by bolts —27— and it is readily apparent that the 110 knife supporting member may be inserted in one of the openings and pushed forward

against the action of the spring —26— until the other end is in position to be inserted in the corresponding opening —10— in the other plate, and that the springs will resiliently hold the knife supporting member from movement in either direction.

It will be readily apparent from the above description that the shredding knives —12— may be used without the knives —19—, or that they may be used in combination with the knives —19— for cutting and shredding at the same time, and that the bottom —29— of the body portion coacts with the knife —12— for positively cutting the material and at the same time acts as a support for the material adapted to be cut.

The angle bar —16— may be provided with any suitable number of slots and knives may be inserted in as many of these slots as is desirable, depending upon the size of the pieces into which the material is sought to be cut.

The operation of the cutting knives is greatly facilitated by reason of the rapid drawing motion, effected by the peculiar shape of the knife, the rotation of the frame causing not only a downward motion of the cutting knife, but a sawing motion by reason of the semi-cylindrical form of the knife blade, whereby the material is more readily and positively cut.

What I claim is:

1. In a vegetable cutter, a rotary frame comprising a pair of substantially circular disks, means for rotating said disks simultaneously, said disks provided with registering openings wholly within the body of the disks, a removable knife seated in said openings and means mounted on one of said disks for preventing movement of said knife in the direction of its length.

2. In a cutter and shredder, a rotary frame, alined openings extending through said frame, a cutting-knife supporting member mounted in said openings, a plurality of circumferentially extending cutting-knives engaged and held in operative position by said member, and means for holding said supporting member against transverse movement.

3. In a cutter and shredder, a rotary frame, a knife supporting member mounted thereon, comprising an angle bar having slots therein, knives, having grooves in their opposite sides, seated in said slots, one side of the angle bar seated in one of the grooves in the side of the knife, a plate seated in the groove upon the other side of the knife, and means for connecting the angle bar and the plate for positively confining the knives.

4. In a shredder, plates journaled on the same axis, said plates provided with openings alined to receive a knife, a knife having a groove therein seated in said openings, a dog mounted on one of said plates and ro-

tating therewith and seated in the groove in the knife.

5. In a vegetable cutter, a shaft, disks mounted on said shaft and rotating therewith and spaced apart to form a rotary frame, said disks provided with alined openings extending through the disks, a removable knife seated in said openings, means for preventing transverse movement of the knife and a vegetable supporting table located at one side of said frame and below the axis thereof.

6. In a vegetable cutter, a rotary frame having end disks spaced apart, alined openings in said disks, a cutting knife supporting member mounted in said openings, a plurality of circumferentially extending cutting knives engaged and held in operative position by said supporting member, and means mounted on one of said disks for preventing movement of said supporting member in the direction of its length.

7. In a vegetable cutter, a shaft, a pair of spaced disks, mounted on said shaft and rotating therewith, rods connecting said disks to form a rotary frame, said disks provided with registering openings, a removable knife seated in said openings, a groove in said knife and a dog pivotally mounted upon one of said disks and adapted to lie in the groove for preventing transverse movement of the knife.

8. In a rotary cutter, a shaft, a pair of spaced heads connected for simultaneous rotation, a plurality of registering openings in said disks, a longitudinally extending knife mounted in one of the openings in each plate, means mounted on one of said plates for preventing transverse movement of said knife, a knife-supporting member seated in an opening in each of said plates, means mounted on one of said plates for preventing transverse movement of said member, and a plurality of axially extending knives supported by said member.

9. In a vegetable cutter, the combination of spaced disks having registering openings, a removable knife seated in said openings, a groove in said knife and a dog pivoted to one of said disks and operably positioned in the groove in the knife.

10. In a vegetable cutter, a rotary frame comprising a pair of substantially circular heads connected for simultaneous rotation, one of said heads provided with a seat for a knife, the other head provided with an opening extending through the body thereof and alined with said seat, a knife positioned in said seat and said opening and removable endwise through said opening, and means mounted on one of said heads for preventing movement of said knife in the direction of its length.

11. In a vegetable cutter, a rotary frame comprising a pair of substantially circular

heads connected for simultaneous rotation, one of said heads provided with a seat for a cutting knife supporting member, the other head provided with an opening extending through the body thereof and aligned with said seat, a cutting knife supporting member positioned in said seat and said opening and removable endwise through said opening, means mounted on one of said 10 heads for preventing movement of said sup-

porting member in the direction of its length, and a plurality of cutting knives carried by said supporting member.

In witness whereof I have hereunto set my hand this 23rd day of November 1912. 15

HARVEY M. DE LINE.
